[57] CLAIM

The ornamental design for a telescope, substantially as shown and described.

DESCRIPTION

FIG. 1 is a perspective view of the telescope showing my new design;

FIG. 2 is a right side elevational view thereof;

FIG. 3 is a left side elevational view thereof;

FIG. 4 is a front elevational view thereof;

FIG. 5 is a rear elevational view; and

FIG. 6 is a top plan view thereof.

The eyepiece in FIGS. 2, 3 and 5 is shown in broken lines for illustrative purposes only and forms no part of the claimed design.
